UNITED STATES PATENT OFFICE.

HENRY HAMMOND, OF HARTFORD, CONNECTICUT.

DESIGN FOR HATCHETS.

Specification forming part of Design No. **11,425**, dated September 23, 1879; application filed August 26, 1879.
[Term of patent 14 years.]

To all whom it may concern:

Be it known that I, HENRY HAMMOND, of Hartford, in the county of Hartford and State of Connecticut, have originated and designed a new, useful, and original Shape or Configuration for a Hatchet, of which the following is a full, clear, and exact description, reference being had to the accompanying drawings, making part of this specification.

Figure 1 shows a side view of my improved design for a hatchet. Fig. 2 shows an end view of the same.

A is the poll. B is the eye or socket. C is the blade or bit.

The poll A is made round with a slightly-convex face. It is partly cylindrical, as shown in the drawings, and is connected with the eye by the curves D, forming a neck. The cross-section of this neck is circular, and it swells out to meet the edges of the eye, as shown in the drawings.

The eye or socket B has its ends in the direction of the handle straight up and down and slightly convex laterally, forming shoulders at D' D'. The sides H of the eye are plain and intersect with the curved neck, so as to form the arched intersection E. The shoulders D' also curve, as shown.

The blade C has side curves, C' C', as shown, and these unite with the straight ends of the eye by the reversed curves G G. The upper parts of the sides of the blade C also curve outwardly and intersect the plane sides of the eye in the arc F.

The sides H H of the eye converge toward the edge of the blade, as shown in the drawings, so that there is a gradual and symmetrical slope from the top of the poll to the edge, and the sides are not bulged out at the eye, as in the usual form.

The surface of the blade C, the ends, front, and rear of the socket B, and the cylindrical surface and face of the poll A are finished bright or polished, while the neck D and sides H are finished dark with the natural surface of the metal as left in tempering.

What I claim as my invention is—

A design for a hatchet in which the poll is partly cylindrical, and is connected with the eye by a curved neck of circular cross-section swelling out to meet the edges of the eye, with the ends of the eye straight up and down and convex laterally, forming shoulders with the neck, the sides of said eye being plane and forming arched intersections with the neck, in which also the side curves of the blade unite with the straight edges of the eye by reversed curves, and the sides of the blade curve outwardly and intersect the plane sides of the eye in an arc, in which also the sides of the eye converge toward the edge of the blade, and in which the neck and sides are finished dark and the rest bright, all substantially as herein shown and described.

HENRY HAMMOND.
